TOY RAILROAD STATION

Robert I. Genin, New Rochelle, and Leon S. Wirsch,
Forest Hills, N.Y., assignors to Child Guidance Toy,
Inc., Bronx, N.Y., a corporation of New York

Filed Mar. 9, 1962, Ser. No. 69,171

Term of patent 7 years

(Cl. D34—15)

FIG. 1.

FIG. 2.

FIG. 3.

FIG. 4.

FIG. 1 is a top plan view of a toy railroad station showing our new design;

FIG. 2 is a side elevational view;

FIG. 3 is a left end elevational view; and

FIG. 4 is a right end elevational view.

The side of the toy railroad station, not shown, is substantially similar to the side shown.

We claim:

The ornamental design for a toy railroad station, substantially as shown and described.
